ELECTRIC TEA KETTLE

William J. Rakocy, Clifton, N.J., assignor to Ronson Corporation, Woodbridge, N.J., a corporation of New Jersey

Filed Aug. 8, 1969, Ser. No. 18,597

Term of patent 14 years

Int. Cl. D7—02

U.S. Cl. D44—25

FIG. 1 is a perspective view of an electric tea kettle showing my new design;

FIG. 2 is a top view thereof;

FIG. 3 is a front view thereof;

FIG. 4 is a side view thereof;

FIG. 5 is a rear view thereof.

I claim:

The ornamental design for an electric tea kettle, substantially as shown.
